ALARM UNIT

Charles R. Suska, Roxbury, and Peter Thomson, Fairfield, Conn., assignors to The Stanley Works, New Britain, Conn.

Filed Sept. 8, 1971, Ser. No. 178,852

Term of patent 14 years

Int. Cl. D29—02

U.S. Cl. D72—1 A

FIG. 1

FIG. 2

FIG. 3

FIG. 4

FIG. 1 is a perspective view looking downwardly towards the front of an alarm unit showing our design;

FIG. 2 is a side elevational view of the alarm unit shown in FIG. 1;

FIG. 3 is a top plan view of the alarm unit shown in FIG. 1; and

FIG. 4 is a rear elevational view of the alarm unit shown in FIG. 1.

We claim:

The ornamental design for an alarm unit, as shown.
